UNITED STATES PATENT OFFICE.

PHINEAS F. KING, OF CINCINNATI, OHIO, ASSIGNOR TO MOSES MOSLER,
OF SAME PLACE.

BURGLAR-PROOF SAFE.

SPECIFICATION forming part of Letters Patent No. 405,563, dated June 18, 1889.

Application filed December 24, 1888. Serial No. 294,499. (No model.)

To all whom it may concern:

Be it known that I, PHINEAS F. KING, a citizen of the United States, and a resident of Cincinnati, in the county of Hamilton and 5 State of Ohio, have invented certain new and useful Improvements in Burglar-Proof Safes, of which the following is a specification.

My invention relates to that class of burglar-proof safes which have circular door-10 openings, and a circular door which is drawn to its seat by screw-threaded connection; and it consists in peculiar means of constructing the screw-threaded inner end of the circular door, whereby the construction is stronger, the safe 15 can be produced at a less cost of labor and material, and the parts are more readily fitted together.

The invention will be first fully described in connection with the accompanying drawings, and will then be particularly referred to and pointed out in the claim.

In the drawings, in which like parts are represented by similar reference-letters wherever they occur throughout the various views, 25 Figure 1 is a vertical transverse sectional view of a safe-body taken through line $y-y$ of Fig. 2, showing the inside of the safe-front and the closed door in elevation. Fig. 2 is a vertical sectional view of the safe-body and 30 closed door, taken through line $x-x$ of Fig. 1.

Referring to the parts, A represents the body of a burglar-proof safe of ordinary construction, having a circular opening in its front wall to receive the circular door B. Upon the inside of the door B is secured a 35 disk C, the periphery of which is screw-threaded to engage the interiorly-tapped ring D, which is screwed onto the disk C. The disk and ring are locked firmly together by keys c, which are driven into keyways cut 40 into the ring and disk after the ring is screwed tight against the inner face of the door.

The ring D is screw-threaded exteriorly to engage an interior tap in the flanged ring E, which is secured on the inside of the safe-45 front around the door-opening by bolts e, which pass through the flange e' of the ring E.

What I claim is—

In a burglar-proof safe of the character described, the combination of the safe-front, 50 having a circular door-opening, the interiorly-screw-threaded ring surrounding said opening; the circular door, the screw-threaded disk secured upon the inner face of the door, the ring D, screwed onto said disk, and the keys 55 for locking the said disk and ring together.

PHINEAS F. KING.
